SUPPORTING DEVICE FOR NEON TUBES

Fred A. Becker, New York, N. Y.

Application January 17, 1939, Serial No. 251,437

3 Claims. (Cl. 248—50)

This invention relates to supporting devices and more particularly to a support designed for use with a luminous tube or what is known in the trade as a neon tube.

An object of this invention is to provide an improved resilient support for a neon or luminous tube.

Another object of this invention is to provide an improved support for a luminous or neon tube which is so constructed that the tube support and the post carried by the support may have substantially universal adjustment so that it will be possible to initially secure one end of the supporting device to a base and subsequently adjust the supports and the posts to conform to the particular sign structure without loosening the supporting devices from the base.

A further object of this invention is to provide a supporting device of this kind which can not only be adjusted in a horizontal plane relative to the base, but may also be adjusted toward or away from the base so that the supporting devices will readily support the returned or reverted portions of the tubes.

To the foregoing objects and others which may hereinafter appear, the invention consists of the novel construction, combination and arrangement of parts as will be more specifically referred to and illustrated in the accompanying drawing wherein is shown an embodiment of the invention, but it is to be understood that changes, variations and modifications may be resorted to which fall within the scope of the invention as claimed.

In the drawing:

Figure 1 is a perspective view of a pair of supporting devices constructed according to an embodiment of this invention mounted on a base which is partly shown in section,

Figure 2 is a transverse sectional view of a supporting post attached to the luminous or neon tube, the tube being shown in section,

Figure 3 is a perspective view of one of the substantially resilient supporting devices,

Figure 4 is a fragmentary sectional view of a modified form of post and the supporting device,

Figure 5 is a fragmentary perspective view of a modification of the structure shown in Figure 3,

Figure 6 is a perspective view of a further modification of this invention, and

Figure 7 is a fragmentary plan view of a modification of the structure shown in Figure 6.

Referring to the drawing and first to Figures 1 to 3 inclusive, the numeral 10 designates gener-

ally a channel-shaped base member which is preferably constructed out of sheet metal and the character T designates a luminous tube which is adapted to be mounted on the base 10. At the present time the tube T is adapted to be secured to the base 10 by supporting and attaching devices which may be swung horizontally relative to the surface of the base 10 and may also be adjusted toward or away from the base 10, the usual form of adjustment being by threading the supporting post through the supporting bracket. However, this form of attaching means is objectional in many respects due not only to the cost of the attaching devices but also to the fact that these attaching devices are so constructed that the insulating post must be relatively long and the length of this post places a limitation on the position of certain portions of the tube T relative to the base 10. Furthermore, the attaching devices at present available are limited in their adjustment so that it is not possible for the attaching devices to be placed on the base 10 in the shop and the tube T then mounted on the attaching devices at the point where the sign is to be erected.

In order therefore to provide an attaching device which is exceedingly simple in construction and at the same time is capable of a wider range of adjustment than the devices at present available, I have provided a substantially resilient supporting member generally designated as 11 which is adapted to be attached at one end thereof by means of a screw or bolt 13 to the base 10. The supporting member 11 in the present instance is constructed of a relatively stiff wire which is provided with a U-shaped lower portion 12 and a U-shaped upper portion 14 which is connected to the lower portion 12 by a connecting member 15. The two portions 12 and 14 together with the connecting portion 15 are formed from a single wire which has a degree of rigidity and also a degree of resiliency so that the reverted portions 12 and 14 may be bent relative to each other in order to position the supporting post 16 in the desired relation to the tube T.

The supporting member 11 is provided with an eye 17 which is integral with one end of the U member 12 and through which the bolt or screw 13 is adapted to engage. A second eye 18 is formed integral with the free end of the U member 14 and this eye 18 is adapted to engage in a groove 19 formed between a pair of flanges 20 and 21 which are formed on the lower end of the supporting post 16. The supporting post

16 is formed of dielectric material and is provided on the upper end thereof with a tube seat or saddle 22. A pair of diametrically opposed and downwardly divergent lugs 23 extend downwardly from the upper end of the post 16 and provide a means whereby a wire 24 may be wrapped about the tube T and then engaged beneath the lugs 23 so as to firmly secure the tube T on the saddle or seat 22.

As shown in Figure 1 the wire supporting member 11 may have the reverted portions 12 and 14 spread apart for a considerable distance so as to position the post 16 a relatively great distance away from the top of the base 10. It will also be noted in Figure 1 that where the post 16 engages a reverted portion designated R of the tube T the U portions 12 and 14 may be compressed so that the post 16 will be positioned and supported closely adjacent the surface of the base 10. If desired the supporting member 11 may be spread apart laterally with the upper eye 18 thereof disposed laterally of the lower eye 17 and this supporting member 11 may be either compressed or extended as circumstances require.

In Figure 4 there is disclosed a supporting post 16^a having a shank 25 provided with opposed flattened portions 26 which are adapted to be engaged by a hook 27 formed at the free end of the upper reverted member 14^a. In other respects the supporting member 11^a shown in Figure 4 is similar to the supporting member 11. The hook 27 is provided with an inwardly offset bill 28 which is adapted to firmly hold the shank 25 within the hook 27.

In Figure 5 there is disclosed a slightly modified form of supporting member 11^b where the lower end of the reverted portion 12^b is provided with a ring 17^b which may be either welded on to the end of the reverted portion 12^b or if desired may be formed by flattening the end of the reverted portion 12^b and then drilling a hole through the flattened portion.

In Figure 6 there is disclosed a further modification of this invention wherein a supporting member 11^c is provided which has only a single U-shaped portion 12^c and an upwardly projecting stem 29 having a socket 30 secured to the upper end of the stem 29. The lower or free end of the U member 12^c is provided with a rectangular plate 31 having an opening 32 therein to receive the fastening or securing bolt or screw. The socket or cup 30 is provided with a split portion 33 and the lower end of a supporting post 16^c is adapted to be frictionally held in the split and resilient socket 30. The supporting member 11^c in the present instance is adapted to be constructed out of a strip of lead or solder and preferably the socket 30 is formed of a resilient material which will frictionally hold the post 16^c therein. The plate 31 secured to the end of the U portion 12^c may be formed of brass or other sheet metal which may be soldered or otherwise attached to the supporting member 11^c.

In Figure 7 there is disclosed a slightly modified form of the structure shown in Figure 6 wherein the supporting member 11^d is constructed of lead or solder and is provided with a round base plate 31^d having an opening 32^d in the center thereof.

In the use of this tube supporting device the supporting member 11 is adapted to have the post 16 engaged with the eye 18 and if desired

the post 16^c may be relatively loosely mounted within the eye 18 so that the post 16^c may be axially adjusted. The eye 17 is initially adapted to be secured by the fastening member 13 to the base 10 and then the tube T may be secured to the post 16 by the strap or wire 24. The position of the post 16 relative to the tube T may be substantially universally adjusted, that is it may be adjusted in a horizontal direction as viewed in Figure 1 or may be adjusted vertically as well as horizontally. With an attaching device of this kind it is not necessary that the eye 18 overlie the attaching bolt 13 as if desired the upper U member 14 may be bent on an angle either horizontal or vertical and the upper leg of the U member 14 may also be bent outwardly as well as either upwardly or inwardly depending upon the position of the particular part of the tube T relative to the base 10.

The tube attaching means hereinbefore described may be constructed at a relatively small cost and due to the substantially universal adjustment of the attaching device this device is capable of wider use than attaching devices heretofore available. With attaching devices heretofore available it has been necessary to provide different sizes of the devices and it has not been possible to secure the attaching devices to the base 10 in the shop. With an attaching means constructed according to this invention the attaching devices may all be secured to the base 10 in the shop and only an approximate adjustment made of the supporting posts 16. The supporting posts 16 may subsequently be shifted laterally and either inwardly or outwardly relative to the base 10 at the time that the posts 16 are tied to the tube T between tie wires 24.

What I claim is:

1. As a new article of manufacture an illuminable gaseous tube support comprising an elongated supporting member formed of substantially non-resilient, readily bendable material capable of being bent without the application of tools and of retaining its bent form, means at one end of said member for receiving a tube supporting post, and means at the other end of said member for receiving securing means to secure the member on a tube support.

2. As a new article of manufacture an illuminable gaseous tube support comprising an elongated supporting member formed of substantially non-resilient, readily bendable material capable of being bent without the application of tools and of retaining its bent form, means at one end of said member for receiving a tube supporting post, said means comprising a socket in which an end of the post is received, and means at the other end of said member for receiving securing means to secure the member on a tube support.

3. As a new article of manufacture an illuminable gaseous tube support comprising an elongated supporting member formed of substantially non-resilient, readily bendable material capable of being bent without the application of tools and of retaining its bent form, means at one end of said member for receiving a tube supporting post, said means comprising an integral eye for receiving an end of the post, and means at the other end of said member for receiving securing means to secure the member on a tube support.

FRED A. BECKER.
